UNITED STATES PATENT OFFICE.

ANTON SCHNEIDER AND ANDREAS SCHNEIDER, OF CHICAGO, ILLINOIS,
ASSIGNORS TO CHARLES L. FORTIER, OF MILWAUKEE, WISCONSIN.

ELECTROHYGIENIC APPARATUS.

SPECIFICATION forming part of Letters Patent No. 637,833, dated November 28, 1899.

Application filed March 17, 1898. Serial No. 674,166. (No model.)

To all whom it may concern:

Be it known that we, ANTON SCHNEIDER and ANDREAS SCHNEIDER, residents of Chicago, in the county of Cook and State of Illinois, have 5 invented certain new and useful Improvements in Hygienic Apparatus, of which the following is a specification.

This invention relates to improvements in hygienic apparatus, and refers more specifically to an improved exercising apparatus so constructed and arranged that the beneficial effect of physical exercise may be combined and experienced simultaneously with the curative and invigorating effect of electricity.

15 The object of the invention is to provide a simple, convenient, and inexpensive apparatus of the character referred to by means of which the operator may be subjected to an electric current while using the apparatus or 20 may exercise therewith without being subject to the current or may use the apparatus simply as a means of taking electrical treatment without exercise, either one at his option.

The invention consists in the matters hereinafter described, and more particularly pointed out in the appended claims, and may be more readily understood by reference to the accompanying drawings, in which—

Figure 1 is a front elevation of a preferred 30 embodiment of our invention, the central portion of the figure being broken out to reduce the size of the same. Fig. 2 is a sectional view taken on line 2 2 of Fig. 1, the scale of said Fig. 2 being reduced from that shown 35 in Fig. 1 and parts of the apparatus being shown in different positions to show the electrical connections more clearly. Fig. 3 is a vertical sectional view through the casing, taken on the indirect line 3 3 of Fig. 1. Fig. 40 4 is a longitudinal vertical axial sectional view of the induction - coil and connected parts. Fig. 5 is an enlarged fragmentary detail view, partly in section, of an end portion of one of the elastic cables or resistance devices, showing particularly the arrangement 45 of the electrical conductors therein.

Referring to said drawings, A designates any suitable case or frame adapted to be supported upon a wall or the like, preferably at 50 about the height of the operator's shoulders,

said case being herein shown as consisting of an oblong rectangular box provided at its front with a door A' and having its back wall a extended both above and below the main body of the box to provide a suitable support 55 through which the attaching-screws a' a² are inserted.

B designates a pair of resistance devices, preferably and as shown in the present instance consisting of elastic cables or cords, 60 each provided at one end with a suitable securing device by means of which it may be attached to the case A or other suitable fixed support, and at its opposite end with a handle or equivalent device constituting an electrode by means of which it may be grasped or engaged by the hand or other part of the operator's person, the securing devices at the attached ends of said resistance devices being desirably and as herein shown made in 65 the form of open hooks b, adapted to engage with screw-eyes which serve as the securing-screws a', hereinbefore referred to, and the handles attached to the opposite ends of said resistance devices being shown as consisting 70 of metal loops b', suitably secured to the cables by means of hooks b² and provided with metallic grips b³. In the preferred form shown herein the elastic cables are made of rubber provided with a suitable fabric covering b⁴, so woven or wound thereon as to permit the necessary extension and contraction of the cords.

C designates a flexible metallic conductor embedded within and arranged to extend 85 throughout the length of each cable B, said conductor being desirably and as herein shown woven within or made to form the core of the outer cord or covering b⁴, which is wound spirally upon the elastic rubber cable. 90 The end portions of the metallic conductors C are secured in metallic contact with the metal thimbles b⁵ upon the ends of the cables and upon which the hooks b b², respectively, are mounted, this connection being conveniently 95 and as herein shown made by removing the covering of said end portions, so as to expose the metallic conductor and soldering or otherwise securing the latter to the interiors of the thimbles, as indicated clearly in detail 100

Fig. 5. Desirably the hooks b or b^2 , or both, will be constructed to have swiveling connections with the cables.

D designates a block or other suitable support adapted to be secured against the wall at a point vertically beneath the case A and near the floor. The block D is provided with a pair of screw-eyes d similar to the screw-eyes a' , hereinbefore referred to, and adapted 10 for engagement with the hooks b of the cables, and the block is preferably secured to the wall or other support by means of thumb-screws d' , so as to be more readily detachable to facilitate its adjustment to different 15 heights or positions.

Referring now to the mechanism whereby the resistance-cables and connected handles may be charged with electricity, E designates an ordinary cell-battery, which may be of any 20 common or preferred make or construction, suitably mounted in the upper part of the case A.

F designates an induction-coil suitably mounted in the lower compartment of the 25 case A. Said coil embraces the usual primary conductor f , having its opposite ends connected with a binding-screw f' , mounted upon a cross-bar or support F' , forming a part of the frame of the coil, and with a yoke f^2 , mounted upon one end of the coil, respectively, and a secondary conductor f^3 , having its terminals connected with binding-posts f^4 f^5 , respectively, also mounted upon the cross-bar F' .

F^2 designates the vibrator or interrupter of 35 the induction-coil, consisting of a strip of spring metal f^6 , having one end rigidly connected with a support f^7 upon the end of the induction-coil frame and arranged to depend 40 thence vertically downward through the opening of the rectangular yoke f^2 , hereinbefore referred to, and carrying at its free end an armature f^8 , arranged opposite to and a short distance from the core F^3 of the induction-coil.

F^4 designates an adjustable contact, herein shown as having the form of a thumb-screw, threaded through the side of the yoke remote from the frame of the induction-coil and arranged 50 to bear at its inner end against the spring-strip f^6 when the latter is in its normal position or unattracted by the core of the magnet. The said spring-strip f^6 is electrically connected with a binding-screw f^9 , mounted upon the cross-bar F' , by means of a conductor f^{10} .

F^5 designates the usual tubular metallic slide arranged to telescope over the core F^3 and within the coils of the induction-coil, 60 whereby the intensity of the induced current may be varied, the outer casing being provided with a suitable aperture opposite the said slide and through which the latter protrudes, so that it may be adjusted without 65 the necessity of opening the door of the case.

G designates an ordinary switch mounted

within the casing and having its terminals g g' connected with conductors g^2 g^3 , leading to one pole of the battery E and to the binding-post f' , respectively. 70

g^4 designates a conductor leading from the other pole of the battery to the binding-post f^9 , and g^5 and g^6 designate conductors leading from the binding-posts f^4 and f^5 to binding-posts a^3 a^4 , respectively mounted upon the lower extension of the casing adjacent to the screw-eyes a' . The terminals or binding-posts a^3 a^4 are severally connected with the adjacent screw-eyes a' by means of conductors a^5 a^6 , and said binding-posts are also connected with binding-posts d^2 d^3 , respectively mounted upon the block D by means of flexible conductors g^7 g^8 . The binding-posts d^2 d^3 are in turn severally connected with the adjacent screw-eyes d of the block D. 80 85

The primary and secondary circuits through the apparatus as thus constructed and arranged may be traced as follows: Assuming the switch G to be closed, the circuit will be from one pole of the battery through 90 conductor g^2 , switch G, conductor g^3 , binding-post f' , and thence through the primary coil to yoke at f^2 through contact-screw F^4 , interrupter F^2 , and conductor f^{10} to binding-post f^9 , and thence by conductor g^4 back to 95 the opposite pole of the battery. The circuit thus closed energizes the magnet and attracts the armature f^8 , thereby interrupting the circuit between the spring-strip f^6 and contact-screw, whereupon the magnet loses its energy 100 and allows the interrupter to drop back and again close the circuit, thus instituting and continuing the alternate making and breaking of the circuit through the primary coil. The circuit of the current induced through 105 the secondary coil extends from the binding-post f^4 through conductor g^5 to binding-post a^3 , thence to screw-eye a' and through the conductor of the cable or resistance device to the handle of the latter, through the body of 110 the person grasping the handles, back through the opposite cable to its screw-eye, thence through conductor a^6 to terminal a^4 , and from there to the binding-post d^5 through conductor g^6 , thus completing the circuit as long as 115 the operator holds both handles. 120

Should the resistance devices be attached to the lower pair of screw-eyes d , the secondary circuit would be from the binding-posts a^3 a^4 to the binding-posts d^2 d^3 , respectively, thence to the lower screw-eyes and through 125 the resistance devices, as before.

The operation of the apparatus will be obvious. The operator, having closed the switch, will grasp one of the grips b^3 of the handles with each hand, thus closing the circuit through the secondary coil, and will go through the usual or any desired series of movements by alternately stretching and relaxing the elastic cables. Should he desire a 130 more intense current than that produced by the battery with the slide in its innermost

position, he may instantly intensify the current by simply drawing out the slide to the desired extent. When it is desired to exercise in a stooping position, to exercise the muscles brought into action by lifting, or to exercise the lower limbs, the elastic cables will be disconnected from the upper screw-eyes and hooked into the screw-eyes of the block D and the exercise continued as before.

10 Obviously any of the usual movements may be made with this exercising apparatus, and it will be further obvious that, should the operator wish, the apparatus may be used for physical exercise without being subject to the electric current by simply opening the switch. On the other hand, should it be desirable to use the battery simply for its therapeutical effect without the accompaniment of physical exercise, the operator will simply close the circuit 15 and grasp the handles, as in the case of an ordinary medical battery.

While we have herein shown and described the resistance devices as consisting of elastic cords, and these are deemed to be a preferred embodiment of this feature of the invention, yet it will be obvious that the same idea may be applied to an exercising apparatus in which the resistance is in the form of weights operated by cords and pulleys or in which 25 the apparatus is differently constructed and arranged from that herein described, the essential idea being to combine a physical exercising apparatus with means for charging it from a source of electricity.

30 We claim as our invention—

1. The combination to form a hygienic apparatus, of a frame or casing adapted to be secured to a wall or like support, a pair of elastic cables forming electric conductors, 35 each provided with a metallic gripping-piece at one end and attached to said frame or casing at the other end, an electric battery and an induction-coil within the casing, electric conductors connecting the battery in circuit with the primary of the induction-coil and conductors connecting the elastic cables in circuit with the secondary of the induction-coil.

2. The combination to form a hygienic apparatus, of a frame or casing adapted to be secured to a wall or like support, a pair of elastic cables forming electric conductors, 40 each provided with a metallic gripping-piece at one end and detachably connected with a fixed contact device, mounted upon said frame or casing, at the other end, an electric battery and an induction-coil within the casing, electric conductors connecting the battery in circuit with the primary of the induction-coil, conductors connecting the said fixed 45 contact devices in circuit with the secondary coil, a block, provided with a second pair of contact devices adapted for engagement with the elastic cables, mounted at a distance from said casing and conductors connecting the 50 contact devices of the block with the contact devices mounted upon the casing.

3. The combination to form a hygienic apparatus, of a frame or casing adapted to be secured to a wall or like support, elastic cables forming electric conductors and each provided with a metallic handle, hook-eyes mounted upon said casing, an electric battery and an induction-coil within the casing, electric conductors connecting the battery in circuit with the primary of the induction-coil, 70 and electric conductors connecting the pair of hook-eyes in circuit with the secondary of the induction-coil.

4. The combination with an exerciser comprising a movable electrode and retracting resistance, of a source of electricity generated independently of the exerciser, and automatic means for producing momentary pulsations of current through said electrode.

5. The combination with an exerciser comprising a movable electrode and retracting resistance, of a source of electricity generated independently of the exerciser, and means for adjusting the strength of current through the electrode.

6. The combination with an exerciser comprising a movable electrode and retracting resistance, of a source of electricity generated independently of the exerciser, and an induction-coil and circuit-interrupter for increasing 95 the physiological effect of the current.

7. The combination with an exerciser comprising a movable electrode and retracting resistance, of a source of electricity generated independently of the exerciser, an induction-coil and circuit-interrupter for intensifying 100 the physiological effect of the current and means for varying the strength of the current.

8. The combination with an exerciser comprising an elastic cable forming an electric conductor and provided with an electrode, of a source of electricity generated independently of the exerciser, and automatic means for producing momentary pulsations of current through said electrode, substantially as and for the purposes set forth.

9. The combination with an exerciser comprising an elastic cable forming an electric conductor and provided with an electrode, of a source of electricity generated independently of the exerciser, and means for adjusting the strength of current through the electrode, substantially as and for the purposes set forth.

10. The combination with an exerciser comprising an elastic cable forming an electric conductor and provided with an electrode, of a source of electricity generated independently of the exerciser, and an induction-coil 125 and circuit-interrupter for increasing the physiological effect of the current, substantially as and for the purposes set forth.

11. The combination with an exerciser comprising an elastic cable forming an electric conductor and provided with an electrode, of a source of electricity generated independ-

ently of the exerciser, an induction-coil, a circuit-interrupter for intensifying the physiological effect of the current, and means for varying the strength of the current, substantially as and for the purposes set forth.

5 12. In hygienic apparatus the combination with a source of electricity, of a suitable support provided with contacts which have electrical connections with said source of electricity, and one or more elastic conducting-cables each provided with an electrode and adapted to be detachably and interchange-

ably connected with said contacts, substantially as and for the purposes set forth.

10 In testimony that we claim the foregoing as our invention we affix our signatures hereto, in the presence of two subscribing witnesses, this 14th day of March, A. D. 1898.

ANTON SCHNEIDER.
ANDREAS SCHNEIDER.
